UNITED STATES PATENT OFFICE.

THEODORE C. STROUT, OF WATERBURY, CONNECTICUT, ASSIGNOR TO THE HART & HEGEMAN MANUFACTURING COMPANY, OF HARTFORD, CONNECTICUT, A CORPORATION OF CONNECTICUT.

SWITCH FOR ELECTROLIERS.

1,172,178.

Specification of Letters Patent.

Patented Feb. 15, 1916.

Application filed June 28, 1912, Serial No. 706,435. Renewed January 18, 1916. Serial No. 72,873.

To all whom it may concern:

Be it known that I, THEODORE C. STROUT, a citizen of the United States, residing at Waterbury, in the county of New Haven 5 and State of Connecticut, have invented a new and useful Improvement in Switches for Electroliers; and I do hereby declare the following, when taken in connection with the accompanying drawings and the characters of reference marked thereon, to be a full, clear, and exact description of the same, and which said drawings constitute part of this application, and represent, in-

Figure 1 a top or plan view of a push button switch constructed in accordance with my invention. Fig. 2 a sectional view showing the switch open. Fig. 3 a sectional view on the line *a*—*b* of Fig. 1. Fig. 4 a sectional view on the line *c*—*d* of Fig. 1, showing the switch turned for one light. Fig. 5 a similar view showing the switch turned for two lights. Fig. 6 shows the switch turned for three lights. Fig. 7 is a diagrammatical view showing the circuits of the switch in the positions of Figs. 2 and 3. Fig. 8 is a perspective view of the contact disk detached. Fig. 9 is a perspective view of the contact disk operating ratchet detached.

30 This invention relates to an improvement in switches for electroliers, and particularly to switches of the push-button type, namely such as are provided with an oscillating switch blade as distinguished from the continuously rotary blade of the rotary snap switch type. In switches of this type the mechanism is usually actuated by a pair of push buttons, the one which makes the circuit being commonly called the "on" and 35 the other which breaks the circuit, the "off" button. In electroliers it is desirable to provide for turning on one light, then two lights, then three or more lights, or in various combinations. Switches usually employed for this purpose are of the turnbutton type having a continuously rotating switch plate as above described.

The object of this invention is to employ 40 a switch of the push-button type, and at the same time provide for turning on an increasing number of lights; and the invention consists in the construction hereinafter described and particularly recited in the claims.

In carrying out my invention, I employ the usual switch housing 2 in which a white 55 button 3 and a black button 4 are mounted in the usual manner to operate a snap switch 5, the ends 6 and 7 of the switch plate being adapted to connect with the contacts 8 and 9 respectively connected with the two wires 60 of the main circuit, that is, the contact 9 is in electrical connection with an inlet wire 10, and the contact 8 is in electrical connection with a wire 11 to one of the lights of the chandelier indicated by *a* in Fig. 7. This 65 snap switch 6 is mounted on a shaft 30. Parallel with, and above the shaft 30 is a shaft 14 which carries a ratchet 13 having four teeth, and this shaft 14 is provided with a square section to be engaged by a 70 snap finger 15 by which it is held against reverse movement. Carried by the white or "on" button 3 is a stud 3^a on which is mounted a spring pawl 12 co-acting with the ratchet. On the shaft 14 is a contact disk 75 or commutator 16 having an insulated section 17 and three contact sections 18, 19 and 20. The binding post 21 which supports the contact 8 is connected by a bus-bar 22 with a contact finger 23 which extends into 80 contact with, and bears against opposite faces of the contact disk 16. On opposite sides of the contact disk 16 are contact fingers 24, 24, 25, 25. The fingers 24 are connected through a wire 26 with a second light 85 *b* as indicated in Fig. 7, while the contact fingers 25, 25, are connected by a wire 27 with a third light *c*. At each inward movement of the black button 4 the switch plate is turned to break connection with the contacts 8 and 9, and hence the lights are put out. Considering the normal position, and 90 as indicated in Figs. 2 and 3 of the drawings, in which case it will be noted that the fingers 24, 24, bear against the insulated section 17 of the contact disk. If, now, the white or "on" button be pressed inward, the switch plate will be moved to close the circuit between the contacts 8 and 9, and hence close the circuit to the light *a*, the position 95 of the parts being as shown in Fig. 4 in which it is noted that the spring finger 23 bears against the insulated section 17 and hence cuts out the contact disk 16. The inward movement of the white button moves 100 the pawl 12, and hence turns the shaft 14,

and this gives the ratchet 15 a quarter turn. An inward push of the black or "off" button will cut out this one light *a*, and turn the shaft 30 in the opposite direction; but during this operation the shaft 14 is held by the snap finger 15 so that the contact disk 16 will be held against reverse movement and the pawl will fall back into engagement with the next succeeding tooth. Then the next inward push on the white button will not only close the circuit through the fingers 8 and 9, but also close the circuit through the arms 23, 23, 24, 24, thus turning on the lights *a*—*b*. An inward push on the black button will extinguish these two lights, and then an inward push on the white button will bring the parts to the position shown in Fig. 6 of the drawings in which the circuit is made not only through the contacts 8 and 9, but through the fingers 23, 23, and 24, 24, and 23, 23, and 25, 25, turning on the lights *a*, *b* and *c*.

It is understood that the return circuit through the lights is on a common conductor 28 to a generator 29. It will be understood that the switch is equally adapted for electroliers having more than three lights as *a* might indicate one light, *b* two additional lights, and *c* three additional lights, or in any other combination desired; and the number of changes may be increased by changing the number of segments in the contact disk 16. It will thus be seen that I have produced a switch for electroliers of the push-button type in which the number of lights desired may be turned on by manipulating the buttons in the usual way. Furthermore, it will be seen that with the oscillating switch mechanism and the rotary commutator means are provided for driving or actuating the commutator by some part of the switch; that in the operation of the switch mechanism the switch plate does not commence to move until the push buttons have reached approximately the end of their travel, the switch plate being then thrown with a quick snap action, while the commutator moves simultaneously with the push buttons, or with the "on" push button, there being a solid and direct driving connection between the two; and it will be further seen that the circuit is controlled by the commutator, or that the commutator makes and breaks the electrical connections with the light circuits before the snap-switch mechanism operates. In other words, the commutator acts to control the light circuits while the current is off, thus obviating any possibility of sparking at the commutator and the consequent danger of fire.

I claim:—

1. In a push-button switch, the combination with a snap switch adapted to close a main line circuit and buttons for operat-

ing the same, of a multiple contact device arranged for selectively controlling branches of the main line circuit, and means connected with the snap switch for operating the multiple contact device. 70

2. In a push-button switch, the combination with a snap switch adapted to close a main line circuit and buttons for operating the same, of a sectional contact disk arranged to selectively control branches of said main line circuit, and connections between said contact disk and snap switch whereby the contact disk is turned by the operation of the snap switch. 75

3. In a push-button switch, the combination with a snap switch adapted to close a main line circuit and push buttons for operating the same, a shaft upon which said snap switch turns, a sectional contact disk arranged to selectively control branches of said main line circuit, a ratchet connected with said contact disk, and a pawl operated by the snap switch for turning said contact disk. 80

4. The combination with a push button snap switch provided with an oscillating switch plate arranged to control a main line circuit and manually operable means for moving said switch plate in both directions, of a rotary commutator arranged to control branches of the main line circuit and driving connections between said switch and commutator. 90

5. The combination with a snap-switch mechanism including an oscillating snap-switch, and manually operable means to cause the movement of the switch plate in either direction, of a commutator arranged to control branches of the main line circuit adapted for step-by-step rotation in one direction, and driving connections between said switch and commutator operative in one direction of movement of said switch plate. 100

6. The combination with a snap-switch mechanism arranged to control a main line circuit and manually operable means for moving the switch plate in opposite directions, of a rotary commutator arranged to control branches of the main line circuit and driving means between said switch and commutator, operative only upon movement of the former in one direction. 115

7. The combination with a push button snap switch arranged to control a main line circuit and manually operable operating mechanism therefor of a commutator arranged to control branches of the main line circuit formed separately therefrom and means connected with the switch for operating the commutator. 120

8. The combination with a snap-switch mechanism, an oscillating switch plate actuated thereby and arranged to control a main line circuit, and manually operable means 125

for moving said mechanism in opposite directions, of a commutator arranged to control branches of the main line circuit adapted for step-by-step rotation in one direction, and means for moving said commutator from one position to another by said operating means as said switch plate is moved.

In testimony whereof, I have signed this specification in the presence of two subscribing witnesses.
